UNITED STATES PATENT OFFICE

2,564,590

INKING MECHANISM FOR ROTARY PRINTING PRESSES

Roy F. Aberle, Portland, Maine, assignor to Southworth Machine Company, Portland, Maine, a corporation of Maine

Original application September 20, 1946, Serial No. 698,252. Divided and this application April 9, 1948, Serial No. 20,086. In Canada September 18, 1947

3 Claims. (Cl. 101—144)

1

This invention relates to printing presses and more particularly to sheet-fed, lithographic, offset presses of the kind illustrated in my co-pending application Serial No. 698,252, filed September 20, 1946 which has matured to Patent No. 2,542,073, granted February 20, 1951 of which this application is a division.

The principal objects of this invention are to provide improved inking mechanism for the press and for the drive for this mechanism and further to improve these mechanisms in such manner as to permit better access to the inner portions of the press such as the main cylinder, and the ink form rolls.

Further objects of the invention and features of improvement will be apparent from this specification and its drawings wherein the invention is explained, by way of example, by the description of a specific mechanism embodying the invention.

In the drawings:

Fig. 1 is a diagram showing the main rolls of the press;

Fig. 2 is an elevation of the upper part of the press showing the upper movable frame of the press raised to give access to normally inaccessible parts;

Fig. 3 is a detail of a portion of mechanism for raising and lowering the upper movable frame of the press;

Fig. 4 is an elevation, partly broken away and partly diagrammatic, showing the form rolls for the main cylinder and mechanism for controlling the operation of these form rolls;

Fig. 5 is a detail view of the control mechanism of Fig. 4, viewed from the left side;

Fig. 6 is a fragmentary view showing the hanger for one of the form rolls and portions of this form roll, the cooperating distributor roll, the upper movable frame and the upper stationary frame;

Fig. 7 is a sectional view taken on the line 7—7 of Fig. 6;

Fig. 8 is a fragmentary view showing the supplemental cylinder and the mounting for its associated form roll and transfer roll, and also showing mechanism for holding this form roll in an inactive position; and

Fig. 9 is a fragmentary view showing the form roll for the supplemental cylinder.

The general construction of the machine is described in my Patent 2,542,073 to which reference may be had for the details of its operation.

As herein illustrated (Fig. 1) the main frame of the press includes opposite interconnected side plate sections 25 which are preferably flanged as at 25^a at their lateral margins, the flanges serving to cover and protect various gears, chains, bear-

2

ings and control mechanisms that are located adjacent to the two side plates 25.

Sheets fed successively by feeding mechanism such as that of my patent 2,497,849 enter the machine from the right as shown in Fig. 1, are temporarily stopped laterally aligned and are then gripped by gripper fingers 32, on a gripper bar 33 carried by chains 180 and advanced to a printing couple. The course of chains 180 is indicated in Fig. 1.

The sheet is carried by the traveling gripper bar 33 to and partly around a rubber covered offset cylinder 40, the offset cylinder having a recess adapted to receive the gripper bar.

As shown in Fig. 1 offset cylinder 40 cooperates with a main cylinder indicated generally at 42. Main cylinder 42 comprises opposite end portions 42^a mounted on a shaft 166, a lithographic plate holder segment 43 having hub

20 portions 43^a also mounted on the shaft 166, and an interchangeable impression segment 44 detachably secured to the opposite end portions 42^a. Depending upon the character of the work being done, impression segments having surfaces 25 of various materials may be used as more fully described hereinafter.

As explained in the above patents, a lithographic plate on segment 43 offsets an image onto the offset cylinder 40, the sheet is then carried in between the offset cylinder and the impression segment 44 of the main cylinder, which results in the image being printed from the offset cylinder 40 onto the lower surface of the sheet.

35 The timing and arrangement of the main and offset cylinders and the feeding mechanism, paper stop fingers, and gripper bar 33 is such that a sheet to be printed is presented to the nip between the offset and main cylinders at each revolution of the main cylinder, or in other words, at each second revolution of the offset cylinder.

The main cylinder 42 is provided with plate-dampening mechanism indicated generally at 50 and plate-inking mechanism indicated generally at 55 so as first to dampen the water-receptive blank portions of the lithographic plate and then to ink the ink-receptive image-carrying portions during the time that the impression surface 44 is cooperating with the offset cylinder 40. Further rotation of the main cylinder then brings the dampened and inked lithographic plate on segment 43 into position to offset its inked image onto the rubber surface 55 of the offset cylinder 40.

A supplemental roll 60, for instance carrying

3

a rubber plate having raised letters, is arranged to offset onto the otherwise blank surface of the impression segment 44 of the main cylinder. The image thus transferred to the impression surface 44 is then printed onto the upper surface of the sheet simultaneously with the printing onto the lower surface of the sheet by offset cylinder 40.

Leaving the nip between the offset cylinder 40 and the impression segment 44, the printed sheet is released by the grippers of bar 33 and simultaneously gripped by a circularly moving second set of grippers which move around axis 71, (Fig. 1), and at the end of an approximately 90° circular travel release the sheet and transfer it to third grippers which are carried by chains 142 in a generally triangular path, as shown in Fig. 1.

On the first or downwardly inclined portion of this triangular path away from the offset cylinder, the sheet may be subjected to a further printing operation. Mechanism for such further printing preferably comprises, one or more rotating serial numbering units and cooperating platen rolls between which the sheet is carried so that the sheet is numbered on its lower surface upon which it had previously received an impression from the offset cylinder.

The chain-carried third grippers then carry the sheet onto the lower horizontal run of their triangular path, in which the grippers are caused to open and drop the sheet, with its offset printed and numbered surface uppermost, onto an automatically lowered stack on a platform on which the newly arrived sheet is aligned both longitudinally and transversely by corner-jogging mechanism the foregoing being described clearly in my aforesaid Patent 2,542,073.

As previously explained, the main press frame includes generally vertical plate sections 25 at opposite sides of the press.

The inking mechanism is carried by two further frames which may be removed from the press.

An upper stationary frame comprising interconnected plates 850 (Fig. 2) rests on cross bars 851, 852 carried by the main frame, and each plate 850 of the upper stationary frame is spaced somewhat inwardly of its adjacent main frame plate 25.

An upper movable frame comprises interconnected plates 855, each of these plates being located between its adjacent upper stationary frame plate 850 and main frame plate 25, and the two interconnected plates 855 of the upper movable frame are pivotally mounted about the axis of the horizontal shaft 857 carried by the upper stationary frame, as indicated in Fig. 2.

The shaft 857 forms the central axis for the drive of mechanism carried by both the upper stationary frame and by the upper movable frame, and is itself driven through suitable gearing from the main cylinder.

An ink fountain indicated generally at 869 (Fig. 1) carried by the stationary upper frame, is provided with an ink fountain roll 870 which delivers ink to a ductor 880 from which the ink is delivered in succession to a transfer roll 890 and a further transfer roll 891. Ductor roll 880 is swung back and forth between ink fountain roll 870 and transfer roll 890 by means of a cam 881 carried by a continuously rotated shaft 882. The ink transfer mechanism, extending from the ink fountain to and including the transfer roll

4

891, is carried by the upper stationary frame comprised of plates 850.

The ink transfer roll 891 delivers ink to an oscillating distributor roll 893 on the shaft 857 at the axis of pivotal connection between the upper stationary frame and the upper movable frame.

Ink travels from the distributor roll 893 to a transfer roll 894, an oscillating distributor roll 895, a transfer roll 898, an oscillating distributor roll 900 on shaft 901, a transfer roll 910, an oscillating distributor roll 911, a transfer roll 915, and an oscillating distributor roll 916 on a shaft 917, all of these rolls having their shafts mounted in the upper movable frame, and the distributor roll 893 also having its shaft 857 mounted in the upper stationary frame.

Form rolls 920, 921 and 922 run in frictional contact with the distributor rolls 893, 900 and 916, respectively.

The shafts 930, 931 and 932 (Fig. 4) of these form rolls are carried by hangers 935, 936 and 937, respectively, which are provided with enlarged upper ends which pivotally seat within bosses 935^a, 936^a and 937^a, respectively, on the upper stationary frame 850, as more fully described below. This mounting of the form roll hangers permits pivotal movement of the form rolls about the axes of the distributor roll shafts so that the form rolls can move toward and from the main cylinder while remaining in operative contact with their distributor rolls.

Each form roll hanger is secured within its boss on the frame 850 by a detachable plate. Thus Figs. 6 and 7 show the hanger 936 with its head portion rotatably seated within boss 936^a and secured in this position by a detachable plate 936^b.

Each form roll 920, 921 and 922 has its shaft mounted in its hangers 935, 936 or 937 by an adjustable mounting such as shown in Figs. 6 and 7 wherein the shaft 931 of form roll 921 is shown as mounted in a block 942. Block 942 is adjustable lengthwise of the bracket 936 by a set screw 943 to adjust the form roll into proper engagement with its cooperating distributor roll.

The pressure of contact of the form rolls 920, 921 and 922 against the plate segment of the main cylinder can be adjusted by set screws 944 (Fig. 4) against which the hangers 935, 936 and 937 abut in the operative positions of the form rolls.

In normal running of the press while the sheets are being properly fed, each form roll 920, 921, 922 is in frictional contact with the lithographic plate on the passing lithographic plate segment 43 of the main cylinder.

During passage of the impression segment 44 of the main cylinder, cam follower disks 930^a, 931^a and 932^a (Fig. 4) on the form roll shafts 930, 931 and 932 make contact with a cam 940 on the main cylinder with the result of shifting the form rolls individually out of position to contact with the impression segment 44.

Cam 940 on the main cylinder overlaps all of the impression segment 44 and also the two gaps between the impression segment 44 and the lithographic plate segment 43 so that the form rolls neither contact with the impression segment nor tend to drop into the gaps between segments of the main cylinder but operatively engage only the lithographic plate segment 43. Each form roll is individually shifted out of operative position by the cam 940 as the form roll is reached by the trailing end of the lithographic plate segment 43 and each form roll is automatically re-turned into operative position by a tension spring

941 as the form roll is reached by the beginning end of the lithographic plate segment 43. Fig 4 shows all three form rolls simultaneously held out of contact with the impression segment by passage of the cam 940.

The upper movable frame comprising the plate member 855, 856, carrying ink transfer mechanism and distributor rolls for the main cylinder, and also carrying inking mechanism for a supplemental printing cylinder as hereinafter described, can be shifted about its pivot 857 to the elevated position of Fig. 2 to expose ordinarily inaccessible parts.

As indicated above, the distributor rolls 893, 900 and 916 are carried by the movable upper frame 855, and when this frame is swung upwardly about shaft 857 both distributor rolls 900 and 916 accompany the upper movable frame and leave their corresponding form rolls 921 and 922.

Bosses 936^a and 937^a, which pivotally support the hangers 936 and 937 of form rolls 921 and 922, and also the detachable plates, such as plate 936^b, which retain the form roll hangers in place in these bosses, are provided with slots indicated at 938 (Fig. 7). These slots have sides which are arcuate and concentric with shaft 857, and permit the distributor roll shafts 901 and 917 to enter and leave these slots as the upper frame 855 swings around shaft 857.

The upper ends of hangers 936 and 937 are also forked to receive the distributor roll shafts 901 and 917 at the axes of pivotal movement of these hangers when the upper movable frame is in its lower position, and these forked portions of hangers 936 and 937 are shaped so as not to interfere with the entrance or exit of shafts 901 or 917 into or from the bosses 936^a and 937^a in any of the angular positions of the hangers 936 and 937.

Rods 840 (Fig. 2), at opposite sides of the press, are pivotally connected at their lower ends to the cross bar 852 of the stationary main frame 25, and are threaded into internally threaded worm wheels 842 (Fig. 3). Worm wheels 842 are engaged by worms 843 on a cross shaft 844, each worm wheel and the shaft 844 being secured to the upper movable frame 855 by a retaining bracket 845 pivotally mounted on the frame 855 at 846. A crank arm 847 on shaft 844 enables the worm wheels 842 to be rotated to screw them up and down the rods 840, thus raising and lowering the upper movable frame 855 and the parts carried thereby. In the raised position of Fig. 2 many normally inaccessible parts of the press are exposed, for example, the form rolls for the main cylinder, and the supplemental printing cylinder subsequently described.

Control of inking mechanism

The inking mechanism is prevented from inking the lithographic plate during continued running of the machine after a sheet has failed to be fed.

Referring to Fig. 4, each of the hangers 935, 936 and 937 shown therein for carrying the form rolls is provided with a cam follower roller 950. A segmental plate 952 is slidable in an arcuate path upon pins 953 which are mounted in the upper stationary side plate 850 and extend through arcuate slots 954 in the segmental plate. Cut-out portions 956 of the segmental plate 952 normally clear the cam follower rollers 950 and are provided with inclined cam surface portions 956^a adapted to contact with and lift the cam 75

follower rollers 950 when the segmental plate 952 is shifted in a clockwise direction from Fig. 4, and so shift the form rolls around their respective distributor rolls and out of contact with the lithographic plate.

Segmental plate 952 is connected by a link 960 to a bell crank 961 which is fast on a shaft 962 rotatable in the upper stationary side plate 850, and the left end of the bell crank 961 is formed as a handle 961^a for convenient resetting of the mechanism.

A lever 965 is forked at its lower end so as to straddle a squared outer end of the shaft 962 which carries the bell crank 961, and is pivotally mounted thereon by means of a pin 965^a so that its upper portion can swing toward and away from the observer in Fig. 4. The upper end of lever 965 carries a cam follower roller 966 adapted to make contact with a cam surface 967 on a plate cam 968 which is carried by the continuously rotating shaft 882 (Fig. 1). A coil spring 970 acting on the lever 965 and upon an enlarged head 965^b of the pivot pin 965^a yielding urges the upper end of the lever 965 away from the observer in Fig. 4 and toward the left in Fig. 5 to carry the cam follower roller 966 into position to be engaged by cam surface 967. When this engagement takes place the cam surface 967 turns the lever 965, shaft 962 and bell crank 961 counterclockwise from Fig. 4, thrusting the connecting link 960 and segmental plate 952 to the right thus throwing the form rolls out of operative position.

In normal feeding of the sheets, such throwing out of the form rolls is prevented by electrically actuated mechanism actuated by the application of pressure to the offset cylinder and hence, indirectly, by the continuous proper feeding of sheets to the press.

The electrically actuated mechanism is fully illustrated and described in my aforesaid patent.

Manual rotation of the shaft 984 may be employed to disconnect the follower roller 966 from the cam surface 967 in returning the form rolls to operative position. When the follower roller 966 has been disengaged from the cam surface 967, the form rolls may be returned to operative position by manually lifting the handle portion 961^a of bell crank lever 961.

I claim:

1. In a lithographic press, a cylinder adapted to hold a lithographic plate, a plurality of ink form rolls adapted to cooperate with said cylinder, an ink fountain, a plurality of distributor rolls normally running in contact with the respective form rolls, a frame on which a plurality of said distributor rolls are mounted, said frame being pivotally mounted upon the axis of another of said distributor rolls, stationary frame means on which said ink fountain, said other distributor roll and said ink form rolls are mounted, means on said stationary frame means for carrying ink from said fountain to said other distributor roll, and means on said pivotally mounted frame for carrying ink between the several distributor rolls.

2. In a lithographic press a cylinder adapted to hold a lithographic plate, an ink form roll adapted to cooperate with said cylinder, a stationary frame, a hanger pivotally mounted in said stationary frame and carrying said form roll, a movable frame pivotally associated with the stationary frame, and a distributor roll adapted to cooperate with said form roll, said distributor roll including a shaft mounted in said

movable frame, and said hanger for the form roll being shaped to receive the distributor roll shaft at the axis of pivotal movement of said hanger and to permit said distributor roll to move with said movable frame into and out of position to engage said form roll.

3. In a lithographic press a cylinder adapted to hold a lithographic plate, an ink form roll adapted to cooperate with said cylinder, a stationary frame, a hanger carrying said form roll, 10 said stationary frame including a boss in which said hanger is pivotally mounted, and a distributor roll adapted to cooperate with said form roll, said distributor roll including a shaft mounted in said movable frame, and said hanger 15 for the form roll being shaped to receive the distributor roll shaft at the axis of pivotal movement of said hanger and said boss being slotted to permit the distributor roll to move with said movable frame into and out of position to engage 20 said form roll.

ROY F. ABERLE.
